United States Patent Office.

CHARLES GOODWIN, OF BEARDSTOWN, ILLINOIS.

Letters Patent No. 84,182, dated November 17, 1868.

IMPROVEMENT IN WINDMILLS.

The Schedule referred to in these Letters Patent and making part of the same.

To all whom it may concern:

Be it known that I, CHARLES GOODWIN, of Beardstown, in the county of Cass, and State of Illinois, have invented a new and useful Improvement in Windmills; and I do hereby declare that the following is a full, clear, and exact description thereof, which will enable others skilled in the art to make and use the same, reference being had to the accompanying drawings, forming part of this specification.

My invention relates to improvements in windmills, whereby it is designed to provide a more simple and efficient apparatus than those now in use; and it consists in the arrangement of parts, as will be described.

Figure 1 represents a plan view of my improved windmill;

Figure 2 represents a side elevation of the same;

Figure 3 represents a face view of the wind-wheel, and

Figure 4 represents a section of the same.

Similar letters of reference indicate corresponding parts.

A represents a circular track, supported by suitable posts, in a corresponding circular base, B, on which is arranged the swinging frame, pivoted to the central axis, and provided with the friction-rollers *a*, *a*, and *a'*; the roller *a'* being suspended by a bracket on the end of the frame C, so as to take under the circular track in a groove therein. The said swinging frame supports the horizontal shaft D of the wind-wheel, in bearings on the top of the same. Upon the top of the bearings of the said shaft is arranged a vane, F, at a slight angle to the shaft, and with reference to the wind-wheel, so that the pressure of the wind on the side of the vane will be in the right direction to counteract the tendency

of the resistance of the vertical shaft to turn the wind-wheel around sideways to the wind.

G represents the wind-wheel, which is attached to the shaft in a manner to receive the air from the direction of the arrows, shown in red in fig. 2, whereby no tail-board or vane for regulating the position of the wheel with reference to the wind is necessary.

The wings H are jointed to the arms *i*, in a manner to admit of their swinging thereon, and are provided on their narrow sides with the wire springs K, which allow them to open when the wind blows hard, and which closes them as the wind subsides, swinging thereby, to regulate the motion of the wheel, as the wind changes.

The ends of the said springs, which bear upon the ring d of the frame of the wheel, are provided with friction-rollers, and the outer ends soldered or otherwise fastened to the wings H.

I do not claim the use of spiral springs, as I am aware that they are not new, and I consider the arrangement adopted by me as superior in every respect.

I claim as new, and desire to secure by Letters Patent—

1. The arrangement of the vane F, in an inclined position upon the shaft D, and operating in connection with the wheel G, as herein described for the purpose specified.

2. The arrangement of the wings H, shafts *i*, straight springs K, and ring d, operating as described for the purpose specified.

CHARLES GOODWIN.
